UNITED STATES PATENT OFFICE.

HARRY TRISCHLER, OF CROOKSVILLE, OHIO, ASSIGNOR TO THE CROOKSVILLE CHINA COMPANY, OF CROOKSVILLE, OHIO, A CORPORATION OF OHIO.

DESIGN FOR A TEAPOT OR SIMILAR ARTICLE.

Application filed December 4, 1925. Serial No. 15,641. Term of patent 7 years.

To all whom it may concern:

Be it known that I, HARRY TRISCHLER, a citizen of the United States, and residing at Crooksville, in the county of Perry and State of Ohio, have invented a new, original, and ornamental Design for a Teapot or Similar Article, of which the following is a specification, reference being had to the accompanying drawing, forming a part thereof, in which—

Fig. 1 is a top plan view and Fig. 2 a side elevation of a teapot, showing my new design.

I claim:

The ornamental design for a teapot or similar article, substantially as shown.

HARRY TRISCHLER.
